DEVICE FOR CONTROLLING VERTICALLY
SLIDING WINDOWS

William Young, Wishaw, Scotland

Application October 27, 1938, Serial No. 237,352
In Great Britain November 2, 1937

8 Claims. (Cl. 268—132)

This invention relates to devices for controlling windows of the vertically sliding type and more particularly to those having means which are rotatable by hand for moving the window to the open or closed position.

In certain types of devices the hand-operated means has to be turned a considerable number of times to operate the window. This is necessary because the pressure on the handle would be too great to operate the handle comfortably without a considerable reduction in gearing.

The object of the invention is to provide simplified means which need not be rotated so many times as heretofore and further to produce a device which will require a small amount of force or pressure to operate it.

Another object of the invention is to provide an improved window which cannot be lowered without operating the winding handle, but which can be closed without touching the operating handle.

A still further object of the invention is to provide means which permit non-rectangular windows to be operated without the employment of skew cut pinions and gearing.

One form of the invention will now be described by way of example with reference to the accompanying drawing, in which:

Figure 1 is an elevation of the device attached to the window frame.

Figure 2 is a sectional view of the device on an enlarged scale.

Figure 3 is a section on line A—A of Figure 2.

Figure 4 is an end view of Figure 2 with a portion of the frame removed.

Figure 5 is a detail.

Figure 6 is a plan of Figure 5 with the bracket omitted.

Figure 7 is an alternative form of construction to Figure 5.

Figure 8 illustrates alternative means for operatively connecting the sliding window to the operating mechanism.

In carrying the invention into effect according to the form illustrated in Figures 1, 2, 3 and 4 as applied, for instance, to half-drop windows, the top or sliding pane 1 is provided with two racks 2, one at each side, which are adapted to be engaged by pinions 3. Mounted upon suitable brackets 4, or the like, which are secured to the two vertical side members 5 of the frame 6 is a hollow horizontal transverse casing 7 and in this is provided a rotatable shaft or scroll 8, the ends of which are supported in suitable bearings 21 at the ends of the said casing and have the pinions

3 mounted thereon which engage the racks 2. The brackets 4 form casings around the pinions 3. If desired, the bearings for the shaft may be provided in the brackets. This shaft 8 is provided with a thread or groove 9 of coarse pitch and mounted upon it is a nut 10 which engages with the thread or groove thereon. The said nut is made rectangular and fits into the casing, thus being prevented from rotating therein. The nut 10 may be made of any other suitable shape, such as oval, and the casing may be of the same shape so that the nut can slide therein but cannot rotate, or if made circular, suitable means may be provided to prevent rotation.

On one side of the nut 10 is provided a number of teeth 11 and on the casing is provided a housing 12 in which is mounted a pinion 13 which engages with the said teeth. A suitable shaft 14 with a handle 15 thereon is secured to the pinion 13 so that rotation of the handle will move the said nut 10 longitudinally along the casing. Suitable bearings are provided for the pinion spindle and the handle in the housing 12 which is mounted upon the casing.

Situated between a collar 16 near one end of the casing and the nut 10 is located a compression spring 17 such that as the nut is moved towards the end of the casing, the spring 17 is compressed and will tend to push the nut 10 in the opposite direction. The spring is so arranged that it balances either wholly or in part the weight of the sliding pane.

By turning the handle only a few turns the nut is traveled longitudinally along the casing for its full travel and by its longitudinal movement will rotate the shaft 8 which in turn will rotate the pinions 3 engaging the racks 2 on either side of the sliding pane of the window which will be moved up or down according to the direction of rotation of the handle. By balancing the sliding pane with the spring, very little force is necessary to rotate the shaft and therefore a few turns of the handle are sufficient to move the window from its extreme open position to its extreme closed position, the number of turns necessary being, of course, dependent upon the pitch of the thread on the shaft and the size of the pinion engaging with the rack.

The pitch of the thread on the shaft 8 is preferably made so that it is non-reversible and is so arranged that the window is locked in any position and cannot be opened or pushed down without rotating the handle, but, on the other hand can be pushed up and shut without touching the handle. This is a great advantage in buses, be-

cause should any windows be left open they can be closed from the outside with a broom or the like when washing the bus instead of having to enter the bus and close all the windows by rotating the handles.

In order to give a constant balance to the sliding pane of the window for all positions, the thread or the scroll upon the shaft may be of varying pitch and in this manner can be made to give a constant pressure to the shaft so as to balance the weight of the window in all positions.

If desired, the casing for housing the threaded shaft or scroll may be mounted directly upon the usual guard rail provided upon the upper edge 15 of the lower or fixed pane of glass of a half-drop window or it may be mounted independently of the guard rail as hereinbefore described, according to circumstances.

Instead of cutting a thread or scroll upon the shaft by machine means, the shaft may be formed of any suitable section, and then twisted to form a thread or scroll thereon. Similarly, the nut may be provided with an internal twisted section corresponding to the shaft by broaching a spiral hole therethrough by means of a drift. When a varying pitch is employed the nut may be provided with a ball 18, as shown in Figures 2 or 3, or with a very small portion of its length having either the internal thread thereon or a cross section corresponding to the cross section of the twisted shaft.

Although the form of the device given above for operating the windows has been described with reference to half-drop windows, it may 35 equally well be applied to whole-drop or full-drop windows. Further, as shown in Figure 8, instead of the sliding pane of the window being actuated by pinions engaging with racks, drums 27, located one on each side of the window frame 40 which wind up tapes, cables or the like 28 may be employed, or any other means may be applied to the ends of the threaded shaft or rod.

According to a further form of the invention applicable to both half-drop and full-drop windows, the transversely extending shaft 8 of said mechanism is provided at each end with a flexible connection 20 as shown in Figures 5 and 6, which is also preferably made torsionally resilient. These flexible connections are connected to two pinions 3, for example, which are mounted in independent housings 19, shown in section in Figure 5, provided upon the sides of the frame or upon the brackets which may be employed to support the winding mechanism. 55 Since the housings are independent the pinions can be mounted at any angle to suit the angle of the racks on windows which are not rectangular, thus saving the cutting of the teeth of the racks or the pinions on the skew.

Instead of making the flexible connection of a strip 20, it may be formed by a portion of a helical spring 21, as shown in Figure 7, or it may be formed by a piece of flexible cable or the like, or in any other suitable manner.

65 The winding mechanism may be mounted upon the sides of the frame, as set forth above, independently of any guard rail which may be provided on the top edge of the lower fixed pane or it may be mounted upon the said guard rail or 70 upon the upper edge of the sliding pane, or upon the top of the fixed frame or pane and the sliding pane suspended from the shaft or scroll by cables, tapes or the like. When the mechanism is mounted upon the sliding pane, the drums or pinions are secured rigidly to the ends of the

shaft or scroll 8 and the racks, if such be employed, are fixed. In the case of full-drop windows, the mechanism may be mounted at the bottom of the frame in the usual manner or on the top of the sliding pane or upon the top of the window frame or pan. In all cases, except where the pinions, drums, or the like are independently mounted in separate housings, they are rigidly secured to the ends of the shaft or scroll 8.

These flexible and torsionally resilient connections will prevent overwinding and will absorb shocks and vibrations so that injury to the operating mechanism is minimised. Further, should the sliding pane be moved up and distortion have occurred so that one corner thereof touches the top rubber of the window before the other corner thereof, the flexible and torsionally resilient connections permit the pinions to rotate relatively to one another and thus sufficient pressure can be exerted on the lower edge of the sliding pane to ensure that the upper edge of the said pane engages with the top rubber of the window frame throughout its length.

I claim:

1. A device for controlling a window pane sliding vertically in a window frame comprising a horizontally disposed shaft having a thread thereon, brackets mounted upon the vertical sides of the said window frame, a tubular casing surrounding said shaft and supported upon said brackets, a nut mounted upon said shaft so as to slide within said tube, means to prevent said nut from rotating, teeth in the form of a rack provided upon said nut, a pinion mounted upon said casing and engaging said rack, a handle for rotating said pinion, means mounted at the end of said shaft adapted to coact with said pane to move it on rotation of the handle, and spring means pushing the said nut along the shaft against the weight of the pane which means permit the said shaft to be rotated in one direction on applying pressure to said pane but prevent it from being rotated in the other direction by pressure applied to said pane in the opposite direction.

2. A device for controlling a window pane sliding vertically in a window frame comprising a horizontally disposed shaft having a thread thereon, brackets mounted upon the vertical sides of the said window frame, a tubular casing surrounding said shaft and supported upon said brackets, a nut mounted upon said shaft so as to slide within said tube, means to prevent said nut from rotating, teeth in the form of a rack provided upon said nut, a pinion mounted upon said casing and engaging said rack, a handle for rotating said pinion, a rack mounted upon each side of the sliding pane, pinions mounted at the ends of said shaft and engaging said racks for moving the sliding pane on rotation of the handle, and spring means pushing the said nut along the shaft against the weight of the pane which means permit the said shaft to be rotated in one direction on applying pressure to said pane but prevent it from being rotated in the other direction by pressure applied to said pane in the opposite direction.

3. A device for controlling a window pane sliding vertically in a window frame comprising a horizontally disposed shaft having a thread 70 thereon, brackets mounted upon the vertical sides of the said window frame, a tubular casing surrounding said shaft and supported upon said brackets, a nut mounted upon said shaft so as to slide within said tube, means to prevent said

nut from rotating, teeth in the form of a rack provided upon said nut, a pinion mounted upon said casing and engaging said racks, a handle for rotating said pinion, a rack mounted upon each side of the sliding pane, pinions mounted in the said brackets, flexible connections connecting the said shaft to the said pinions, said pinions engaging said racks for moving the sliding pane on rotation of the said handle, and spring means 10 pushing the said nut along the shaft against the weight of the pane which means permit the said shaft to be rotated in one direction on applying pressure to said pane but prevent it from being rotated in the other direction by pressure applied 15 to said pane in the opposite direction.

4. A device for controlling a window pane sliding vertically in a window frame comprising a horizontally disposed shaft having a thread thereon, brackets mounted upon the vertical sides 20 of the said window frame, a tubular casing surrounding said shaft and supported upon said brackets, a nut mounted upon said shaft so as to slide within said tube, means to prevent said nut from rotating, teeth in the form of a rack provided upon said nut, a pinion mounted upon said casing and engaging said rack, a handle for rotating said pinions, drums mounted in the said brackets and connected to said shaft, flexible 25 connecting members wound round said drums and connected to said sliding pane for moving it up, and spring means pushing the said nut along the shaft against the weight of the pane which means permit the said shaft to be rotated in one direction on applying pressure to said pane but 30 prevent it from being rotated in the other direction by pressure applied to said pane in the opposite direction.

5. A device for controlling a window pane sliding vertically in a window frame comprising a horizontally disposed shaft having a thread 40 thereon of varying pitch, brackets mounted upon the vertical sides of the said window frame, a tubular casing surrounding said shaft and supported upon said brackets, a nut mounted upon said shaft so as to slide within said tube, means to prevent said nut from rotating, teeth in the form of a rack provided upon said nut, a pinion mounted upon said casing and engaging said rack, a handle for rotating said pinion, means 45 mounted at the end of said shaft adapted to coact with said pane to move it on rotation of the handle, and spring means pushing the said nut along the shaft against the weight of the pane which means permit the said shaft to be rotated in one direction on applying pressure to said pane but prevent it from being rotated in the other direction by pressure applied to said pane in the opposite direction.

6. A device for controlling a window pane sliding vertically in a window frame comprising a horizontally disposed shaft having a thread 50 thereon of varying pitch, brackets mounted upon the vertical sides of the said window frame, a tubular casing surrounding said shaft and sup-

ported upon said brackets, a nut mounted upon said shaft so as to slide within said tube, means to prevent said nut from rotating, teeth in the form of a rack provided upon said nut, a pinion mounted upon said casing and engaging said rack, a handle for rotating said pinion, a rack mounted upon each side of the sliding pane, pinions mounted at the ends of said shaft and engaging said racks for moving the sliding pane on rotation of the handle, and spring means pushing the said nut along the shaft against the weight of the pane which means permit the said shaft to be rotated in one direction on applying pressure to said pane but prevent it from being rotated in the other direction by pressure applied to said pane 15 in the opposite direction.

7. A device for controlling a window pane sliding vertically in a window frame comprising a horizontally disposed shaft having a thread 20 thereon of varying pitch, brackets mounted upon the vertical sides of the said window frame, a tubular casing surrounding said shaft and supported upon said brackets, a nut mounted upon said shaft so as to slide within said tube, means to prevent said nut from rotating, teeth in the form of a rack provided upon said nut, a pinion mounted upon said casing and engaging said 25 racks, a handle for rotating said pinion, a rack mounted upon each side of the sliding pane, pinions mounted in the said brackets, flexible 30 connections connecting the said shaft to the said pinions, said pinions engaging said racks for moving the sliding pane on rotation of the said handle, and spring means pushing the said nut along the shaft against the weight of the pane 35 which means permit the said shaft to be rotated in one direction on applying pressure to said pane but prevent it from being rotated in the other direction by pressure applied to said pane 40 in the opposite direction.

8. A device for controlling a window pane sliding vertically in a window frame comprising a horizontally disposed shaft having a thread 45 thereon of varying pitch, brackets mounted upon the vertical sides of the said window frame, a tubular casing surrounding said shaft and supported upon said brackets, a nut mounted upon said shaft so as to slide within said tube, means to prevent said nut from rotating, teeth in the form of a rack provided upon said nut, a pinion mounted upon said casing and engaging said 50 racks, a handle for rotating said pinions, drums mounted in the said brackets and connected to said shaft, flexible connecting members wound round said drums and connected to said sliding pane for moving it up, and spring means pushing the said nut along the shaft against the weight of the pane which means permit the said shaft to be rotated in one direction on applying pressure to said pane but prevent it from being rotated in the other direction by pressure applied to said 55 pane in the opposite direction.

WILLIAM YOUNG.
